US0D1085882S

(12) **United States Design Patent** (10) **Patent No.:** **US D1,085,882 S**
(45) **Date of Patent:** **** Jul. 29, 2025**

(54) **PACKAGING BOTTLE**

(71) Applicant: **SUNTORY HOLDINGS LIMITED**,
Osaka (JP)

(72) Inventor: **Daisuke Ogino**, Tokyo (JP)

(73) Assignee: **SUNTORY HOLDINGS LIMITED**,
Osaka (JP)

(**) Term: **15 Years**

(21) Appl. No.: **29/961,055**

(22) Filed: **Sep. 4, 2024**

Related U.S. Application Data

(62) Division of application No. 35/518,278, filed on May 24, 2023 (U.S. filing date under 35 U.S.C. 384), and having an international filing date of May 24, 2023.

(57) **CLAIM**

The ornamental design for a packaging bottle as shown and described.

DESCRIPTION

FIG. 1 is a front elevational view of a packaging bottle, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines illustrate portions of the packaging bottle that form no part of the claimed design.
